(57) **CLAIM**

The ornamental design for an endoscope distal tip as shown and described.

DESCRIPTION

FIG. 1 is a top rear perspective view of an endoscope distal tip showing our new design;

FIG. 2 is a top front perspective view thereof;

FIG. 3 is a bottom rear perspective view thereof;

FIG. 4 is another bottom rear perspective view thereof;

FIG. 5 is a front elevational view thereof;

FIG. 6 is a rear elevational view thereof;

FIG. 7 is a left elevational view thereof;

FIG. 8 is a right elevational view thereof;

FIG. 9 is a top plan view thereof; and,

FIG. 10 is a bottom plan view thereof.

The broken lines depict portions of the endoscope distal tip that form no part of the claimed design.

1 Claim, 3 Drawing Sheets
